UNITED STATES PATENT OFFICE.

EARL F. NIEHAUS, OF NOKOMIS, ILLINOIS.

RAIL-JOINT.

1,319,169.

Specification of Letters Patent. Patented Oct. 21, 1919.

Application filed April 25, 1919. Serial No. 292,530.

To all whom it may concern:

Be it known that I, EARL F. NIEHAUS, a citizen of the United States, residing at Nokomis, in the county of Montgomery, 5 State of Illinois, have invented certain new and useful Improvements in Rail-Joints; and I do hereby declare the following to be a full, clear, and exact description of the invention, such as will enable others skilled in 10 the art to which it appertains to make and use the same.

This invention relates to novel and useful improvements in rail joints, the object thereof being to provide a simple and novel 15 construction for joining the meeting ends of rails so as to obviate the necessity of employing the usual fish plates, connecting bolts and other parts likely to become loose, thereby reducing the cost of maintenance 20 and also providing a joint which will keep the tread surfaces of the meeting ends of the rail sections in alinement or practically continuous, thus forming a smooth tread surface over the joint, so as to do away with 25 the usual hammering noise, as the car wheels pass over the joints, as is common with joints as at present commonly used.

A further object of the invention is to provide an improved rail joint, in which the 30 meeting ends of the rail sections are locked together in a novel manner so as to prevent displacement thereof one relative to the other in a vertical or lateral direction, the joints being so arranged as to permit the interfitting of the ends thereof, by raising the 35 end of one rail section remote from that which is being joined to another rail section, while the latter rail section is in position and held from displacement or from slipping 40 relative to the rail section which is being applied, thereby facilitating the joining of the meeting ends of the rail sections, as distinguished from that type of joint wherein it is necessary to dispose both rail sections 45 in a raised position angularly with respect to one another in joining the same.

With the above objects and others in view, as will appear, as the specification proceeds, the invention comprises certain novel arrangements of parts as will be hereinafter 50 more fully pointed out and claimed.

Reference is had to the accompanying drawings, forming a part of this application, wherein like reference characters indicate corresponding parts throughout the 55 specification and wherein:

Figure 1 is a side elevation of the meet-

ing ends of two rail sections having the improved joint;

Fig. 2 is a similar view showing the manner of assembling or connecting the rail sections;

Fig. 3 is a perspective view of one end of each rail section and

Fig. 4 is a similar view of the opposite end.

Referring to the drawings in detail, the abutting ends of two rail sections are indicated at 10 and 11, said rails having the usual base 12, web 13 and head or ball 14. 70 The rail end 10 is provided in its web portion with an undercut arcuate recess 15 leading from the abutting end thereof and having the walls 16 and 17 thereof located on concentric circles. This recess is open at the 75 end of the rail and at the top is limited by the bottom face of the ball 14, thus providing an overhanging lip 18 with its bottom edge forming the wall 17, said lip tapering in the direction of formation of the 80 recess.

The wall 16 is spaced from the base of the rail, and at either side of the web, longitudinal rectangular projections 19 are formed terminating in alinement with the abutting 85 end of the rail and suitably formed therewith against the base 12. Either this section or the other section now to be described, may be applied by tilting it upwardly to engage the opposite section, so long as the 90 angular relation is as shown in Fig. 2 of the drawings.

The rail end 11 has formed upon the web thereof, an extension 20 with a convex edge 21 and a concave upper edge 22, both being 95 formed on concentric circles and the arcuate recess forming the upper edge extending from a line coincident with the bottom of the tread or ball 14, to a point slightly below the same. The free upper edge of the 100 projection extends horizontally as shown at 23, being continuous with the top portion of the web where it leaves the bottom face of the tread or ball 14 forming the head of the rail, this projection being designed to exactly fit the recess 15 in the rail section 10. At either side of the web portion of the rail section 11, there is provided over the base 12, vertical and longitudinal projections 24 having the ends thereof projecting beyond the abutting end of the rail section 11 and formed with bottom recesses 25 having convex bottom edges 26 tapering toward their free ends which are disposed

uppermost. These recesses are provided with end walls 27 terminating at a spaced distance above the base of the rail, at which point the walls 26 of the recesses 25 are continued toward the free extremities of the projections 24, the upper surfaces of which are preferably disposed on a horizontal plane and spaced apart at either side of the rail web immediately below the bottom edge 10 of the extension or tongue 20.

In this manner, by tilting either the rail section 10 or the rail section 11 upwardly while the opposite rail section is anchored to the ties, the tongue or extension 20 may be 15 caused to enter the recess 15 in the manner clearly shown in Fig. 2 of the drawings. During this engagement, the projections 24 through the medium of the convex lower edges of the extensions thereof, will ride 20 upon the rectangular projections 19, the tongue or extension 20 riding against the convex and concave walls of the recess 15 until the edge 23 abuts the bottom of the wall of the rail section 10 with the projection or overhanging lip portion 18 extending 25 into the recess 22, to hold the rail sections against longitudinal displacement one with respect to the other. By disposing the projections 24 upon opposite sides of the rail 30 section 11, the rail section 10 will be held therebetween, thereby preventing lateral displacement of one section relative to the other. However, the parts are so interfit- 35 tted as to allow sufficient contraction and expansion to prevent injury to the road bed, between seasons. Also, the engagement of the projections 24 through the medium of the substantially horizontally positioned lower convex edges thereof with the pro- 40 jections 19, will serve to support the tread surfaces in alinement to form a substantially continuous tread surface so as to do away with the hammering of the car wheels when the latter pass over the joint, as com- 45 monly occurs owing to the car wheels striking the ends of the rails with the subsequent ramming and battering of the rails, due to the construction of the joint, as at present used. The joint is also preferably 50 placed directly over a railroad tie, so as to give greater sustaining power, and by reason of the arcuate formation of the edge portions of the interfitting parts, angular movement relatively of the rail sections, 55 will not result in the destruction of the meeting ends of the rail sections and they may be readily displaced one with respect to the other, without the usual difficulties caused by the use of fish plates, bolts and the 60 like nor the high cost of maintenance resultant therefrom.

What is claimed is:

1. A rail joint comprising two rail sec-

tions, one of said rail sections having a recess formed in the free edge of the web 65 thereof extending to the base of the ball of the rail section and having a concave bottom wall and a convex top wall forming an overhanging projection, said recess terminating spaced from the base of the rail, projections 70 upon the base of the rail adjacent to the web thereof having horizontal bearing faces and the other rail section having an extension upon the web thereof with a convex bottom wall and a concave top wall forming a 75 recess, the free edge of the extension extending horizontally to abut the end of the recess and the overhanging projection of the first named rail section engaging in the recess formed at the top of the extension, and projections upon either side of the web portion and the second rail sections to bear 80 upon said horizontal bearing surfaces, as and for the purposes specified.

2. A rail joint comprising two rail sec- 85 tions, one of said rail sections having a recess formed in the free edge of the web thereof extending to the base of the ball of the rail section and having a concave bottom wall and a convex top wall forming an over- 90 hanging projection, said recess terminating spaced from the base of the rail, projections upon the base of the rail adjacent to the web thereof having horizontal bearing faces and the other rail section having an extension 95 upon the web thereof with a convex bottom wall and a concave top wall, the free edge of the extension extending horizontally to abut the base of the ball of the rail section first mentioned beneath 100 the ball thereof and the overhanging projection of the first named rail section engaging in a recess formed at the top of the extension, and projections upon either side of the web portion of the second rail sections, 105 said projections having extensions produced beyond the ends of the second rail section, adapted to abut with the end of the first rail section and having convex bottom edges, 110 said extensions tapering toward their free ends and the bottom edges thereof terminating spaced from the base of the rail to bear and movably engage the horizontal bearing faces of the projections of the first section, said extensions being designed to 115 engage upon opposite sides of the web portion of the first named rail section and permitting engagement or disengagement of the rail sections with one tilted upwardly angularly with respect to the other.

In testimony whereof, I affix my signature, in the presence of two witnesses.

EARL F. NIEHAUS.
